MISSOURI.

Brake-Shoe.

1,087,676.

Specification of Letters Patent.

Patented Feb. 17, 1914.

Application filed July 20, 1912. Serial No. 710,704.

To all whom it may concern:

Be it known that we, JOHN J. MORSE and WALTER S. GEMMER, citizens of the United States, residing at St. Louis, State of Missouri, have invented and discovered certain new and useful Improvements in Brake-Shoes, of which the following is a specification.

Our said invention consists in certain improvements in the details of construction and arrangement of parts of brake shoes for railway locomotives and cars, relating particularly to the type of shoe provided with reinforcement of steel or other appropriate metal in its back, whereby certain economies and advantages are secured in the construction and use of such a shoe, all as will be hereinafter more fully described and claimed.

Referring to the accompanying drawings which are made a part hereof and on which similar reference characters indicate similar parts, Figure 1 is a longitudinal sectional view of a shoe of our improved construction in which attaching hooks are shown in whole lines and an attaching lug indicated by dotted lines, Fig. 2 a plan view of the back side thereof, but showing the attaching lug as well as the hooks in whole lines for illustrative purposes only, Fig. 3 a detail cross section on the dotted line 3—3 in Fig. 2, the bolt being shown therein, Fig. 4 a detail plan view to more clearly illustrate the preferred form of slot for attaching the lug to the steel back, Figs. 5 and 6 an edge and plan view respectively of the end hook for connection with the brake head, Figs. 7 and 8 a side elevation and end view, respectively, of the center lug for key connection with the brake head, Figs. 9 and 10 similar views of a modified form of said lug, Fig. 11 a detail plan view showing a modified form of the slots in the steel back, Fig. 12 a similar view of another modified form, Fig. 13 a detail side elevation of another modification in the form of lug for key connection, such as will be used with the form of slot shown in Fig. 11, Figs. 14 and 15 a side elevation and end view respectively of another modified form of the center lug, Fig. 16 a side elevation of another form of lug, Figs. 17 and 18 detail views showing modifications in the arrangement for attaching the hooks, Fig. 19 a sectional view showing the brake shoe attached to the brake head by the center lug, Fig. 20

a plan view of the reinforce plate separately, 55 Figs. 21 and 22 detail views showing the use of a multiple of the attaching lugs, and Figs. 23, 24 and 25 details showing another modification in the form of attachment between the lug and the steel back. 60

In said drawings the portions marked A represent the body of the shoe, B the reinforcing plate or "steel" back, C end attaching hooks, and D the center attaching lug.

In a general way the construction of the 65 shoe shown is similar to other shoes in common use, the invention residing chiefly in the details of construction. Said shoe is formed to extend across the flange as well as the tread of the wheels, although we do 70 not desire to be understood as confining our said invention to this form.

In referring to the reinforcing plate B as a "steel back" it will be understood that the term is used in the conventional trade sense 75 and that while the metal of which the plate is composed may be, and probably will commonly be steel, yet any ductile, malleable, or other suitable metal may be used.

One of the leading features of our improved shoe is that it is adapted to be attached to the brake head by any of the standard methods and also to be used on either end of said head. In Fig. 1 we show hooks as the attaching means, in Fig. 19 a 80 center lug with hooks broken off and arranged for key in line with shoe, in Fig. 22 multiple lugs and arranged for cross keys, while in Fig. 2, to better illustrate in various forms, we show both hooks and a 85 center lug in position for use. It will be understood, however, that only one form need be employed when the shoe is in use. The hooks may be bent out of the way, or broken off, when the lugs are in use, and 90 the lugs removed when a hook is to be used, and, generally, that only the parts needed for the particular use need be left on the shoe, the several means being provided to adapt a single shoe for use in any 95 of the various positions and by any of the standard methods. By means of this construction a shoe is provided which is reversible and can be used either as a right-hand or a left-hand shoe, and with a lug for attachment (either single or multiple) one shoe is adapted for use in any position 100 and with any form of attachment common

in standard equipment, thus avoiding the necessity of carrying difficult styles in stock to meet different requirements and adding materially to the value of the shoe in use from an economical standpoint.

Said reinforcing plate, or "steel back," B is preferably formed with a portion cut out between the points 10 and 11 on the side which forms the flange of the shoe and this portion of the steel back is utilized to form the center lug D. Elliptical holes 25 are formed near each end for the bolts 12, and other holes 13 are formed near the center, being preferably punched downwardly to form inturned projections 14, which furnish additional anchoring points for tying the reinforcing plate to the cast metal body of the shoe. Other openings 15 and notches 16 and 17 are formed in the flange side of said plate to afford better anchoring means to unite the steel back and the cast body of the shoe.

The attaching hooks C are of the form best shown in Figs. 1, 5, and 6, and are formed with openings 18 adapted to embrace the inturned projections 14 of the openings 13 in the steel back, and thus form a secure connection between said hooks and said back and when cast into the shoe afford a very solid and safely interlocked connection between the several parts. They are also formed with elongated holes 51 to register with bolt holes 50. The hook ends extend up over the ends of the steel back or reinforcing plate in position to engage with the brake head in the usual manner. In Fig. 17 is illustrated another form wherein the inner end of the shank of hook C is upturned through perforation in steel back B, and in Fig. 18 a space is shown between the upturned part and the end of the slot to receive a portion 52 of the cast metal and thus more securely fasten said parts together.

The preferred form of the lug D is illustrated in Figs. 7 and 8, consisting of a steel or other appropriate metal strap, or plate, preferably of the same metal as the reinforcing plate, bent U-shaped and formed with notches 19 in its opposite edges which are adapted to engage or interlock with the edges of the slot in the steel back and are preferably formed extended beyond said notches 19 and with other notches 20 in their edges in the extended portions, which serve to interlock with the metal of the body when said body is cast around them. In the preferred form said lugs are interlocked with the steel back by means of an opening therein as best illustrated in Figs. 2 and 4, of a substantially rectangular form slightly longer in one direction than the other and extending with the long sides at an angle with the edges of the steel back. The legs of the lug are inserted between the ends of said slot until the notches 19 register with

the plate when said lug is turned to stand square across said steel back with its notches engaged with the edges of the plate surrounding the slot therein and with its edges abutting shoulders s (Fig. 4) which stop said lug and afford a bearing therefor in perfect central alinement with the shoe, thereby insuring perfect connection with the brake head. A secure inter-locking connection is thus formed and when the metal is cast around the inwardly projecting ends filling the openings in the steel back flush with its outer face, and further interlocks with the notches 20 therein, a connection is formed which not only supports said lug firmly to the body of the shoe, but also serves to lock the steel back, or reinforcing member, and its center to said body, affording a very secure and at the same time comparatively simple construction.

In Figs. 9 and 10 we have illustrated another form of center lug in which the lower ends of the lug are bent horizontally, forming horizontal flanges 21 which extend under the edges of the reinforcing member and form a secure inter-locking connection. It will be noted that the flanges 21 are somewhat below the notches 19 having room for cast metal between the bottom of said reinforcing member and said flanges, which thus have their bearing on cast metal and not on the reinforcing member.

In Fig. 11 we have illustrated a modified form of slot in the steel back in which a lug such as shown in Fig. 13 may be inserted, the ends of the lugs being inserted through the long sides of the slot and then the lug as a whole moved to one side, the slots 53 in the ends of the lugs engaging over the tongues 54.

In Fig. 12 we have illustrated a slightly different form of slot in the steel back with which a form of lug such as shown in Figs. 14 and 15 will interlock.

In Fig. 16 we have shown a center lug formed with a narrower top than base, otherwise substantially the same as the lugs shown in Fig. 14, except that it is tapered to conform to the contour of the recess in the Master Car Builders' standard brake head.

In Fig. 23 we have illustrated another modification wherein the steel back, or reinforcing member, is formed with central recesses in its edges and the lug is formed as shown in Figs. 24 and 25 adapted to be spread out to permit the notches 19 to engage the ends of said recesses and be then sprung, or bent, inward so as to interlock therewith, the lower ends of the legs projecting into the cast metal of the body as in the other forms.

While we have illustrated a single lug it will be understood, of course, that we may use a multiple of lugs if found desirable.

and while we have illustrated the lug as positioned so that its opening will extend longitudinally of the shoe, yet it may be placed so that its opening will extend transversely of the shoe. By such a construction the connection with the brake head can be made by means of a cross pin as well as with a key, both types of shoes and connections being in common use on various railroads. In Figs. 21 and 22 we have illustrated such modifications.

By these various improvements in the construction of shoe it will be readily seen that we have provided a single construction embodying the advantages and capable of the uses of several different forms in common use, thereby effecting material and practical economies not only in the use, but in the manufacture of the shoe, inasmuch as a single set of dies is sufficient to manufacture a shoe which takes the place of several styles of shoes heretofore used requiring several sets of dies in their manufacture, all of which are required to be kept in stock to supply the different purposes of such shoes.

The long elliptical holes, or slots, 25 and 51 are for the purpose of covering the variation in the location of the centers of the bolts 12 to accommodate various railway specifications in this particular, which vary as to the distance between the two bolt centers, usually requiring different styles of heads for different specifications. By this invention we, therefore, eliminate this objection 35 and adapt the single reinforcing member in this particular for any character of specification. It will also be seen that said reinforcing member, or steel back, has a recess 26 at each end to receive the hooks C and 40 hold them in proper alinement during molding and also form a rigid connection with the reinforcing member, and prevent said hooks from moving to one side or the other.

Other modifications in form and detail, 45 apparent to those skilled in the art, are obviously within the scope of our said invention.

Having thus fully described our said invention what we claim as new and desire to 50 secure by Letters Patent is:

1. A brake-shoe comprising a body formed of cast metal with a reinforcing member cast therein and connected thereto by interengaging connections, said member formed 55 with a central opening to receive an attaching lug, and said lug formed with interlocking notches and adapted to be inserted in said central opening in one position and moved after being inserted to interlock said 60 notches with the edges around said opening, substantially as set forth.

2. A brake-shoe provided with a reinforcing member formed with a lug receiving slot, and a center attaching lug formed with 65 interlocking portions and secured thereto by

an interlocking connection, said parts being formed to interlock by inserting said lug through one portion of a slot in said reinforcing member and then moving the same bodily to engage the interlocking portions, 70 substantially as set forth.

3. A brake-shoe provided with a reinforcing member having an opening longer in one direction than the other, a lug adapted to be inserted in said opening in the long 75 direction and formed with notches in its sides adapted to receive the edges of said reinforcing member surrounding said opening and permit said lug to be moved to secure an interlocking connection, substantially 80 as set forth.

4. A brake-shoe provided with a reinforcing member formed with an opening longer on one side than on the other, an attaching lug adapted to be inserted in said opening in the long direction and formed with notches to engage the edges around said opening when moved after being inserted to register therewith, and with projecting lower ends adapted to be embedded 90 in the cast metal of the shoe body, substantially as set forth.

5. A brake-shoe comprising a cast metal body, a reinforcing member formed with an interlocking opening for an attaching lug, 95 and an attaching lug mounted in said opening and adapted to be interlocked with the edges around said opening by moving the same after being inserted, substantially as set forth.

6. A brake-shoe comprising a cast metal body, a reinforcing member formed with in-turned projections and openings to form anchor connections between the back and the body, and end attaching hooks formed with 105 openings adapted to connect with said projections on the underside of said member and extending outward and over the ends of said shoe, substantially as set forth.

7. A brake-shoe formed with a cast metal 110 body and a reinforcing member having projections, said body and member being cast together with interlocking portions, and an attaching hook the shank of which extends between said reinforcing member and body 115 and connects with a projection on said member, substantially as set forth.

8. A brake-shoe comprising a cast metal body, a reinforcing member cast therein and formed with interengaging parts and with a 120 recess in the end thereof, and an attaching hook secured to said member between its inner face and the body with its end passing over the end of said member and engaging said recess and its shank connected 125 to a part of said member, substantially as set forth.

9. A brake-shoe comprising a cast metal body, a reinforcing member having projections cast thereon, and a hook the shank of 130

- which is embedded in said cast metal body under said member and interlocks with a projection thereon, substantially as set forth.
10. A brake-shoe comprising a cast metal body, a reinforcing member therein, and a center attaching lug the legs of which extend through appropriate openings in said member and have interlocking portions engaging the edges of said opening and are elongated and have other engaging portions embedded and supported in said cast body, substantially as set forth.
11. A brake-shoe comprising a cast metal body, a reinforcing member therein, and an attaching lug secured thereto by formations interlocking with said member and formed with inter-engaging projections extending beyond said member into the metal of the body, substantially as set forth.
- 20 12. A brake-shoe comprising a cast body, a reinforcing member therein formed with an aperture to receive the attaching lug, said aperture being formed to admit the lug and permit it to be moved so it will interlock with said reinforcing member, shoulders being formed in the edges surrounding said aperture in position to stop the movement of the lug in correct alignment with the shoe, substantially as set forth.
- 30 13. A brake shoe comprising a ductile metal back provided with a projecting tongue and a ductile metal fastening lug through which said projecting tongue passes.
14. A brake shoe comprising a ductile metal back provided with integral laterally projecting parts and a ductile metal fastening lug through which said projecting parts pass.
15. A brake shoe comprising a cast metal body, a ductile metal fastening lug and a ductile metal back provided with laterally projecting parts passing through the side walls of said fastening lug.
16. A brake shoe comprising a cast metal body, a ductile metal fastening lug having its lower ends embedded in the cast metal body and a ductile metal back having laterally projecting parts extending through the sides and over the extreme lower ends of the ductile metal lug.

In witness whereof, we have hereunto set our hands and seals at St. Louis, Missouri this 12th day of July, A. D., nineteen hundred and twelve.
